E. McCORMICK

FOOT CLEANER

Filed May 22, 1922

Patented Aug. 21, 1923.

1,465,736

UNITED STATES PATENT OFFICE.

ENEAS McCORMICK, OF CALGARY, ALBERTA, CANADA.

FOOT CLEANER.

Application filed May 22, 1922. Serial No. 562,759.

To all whom it may concern:

Be it known that I, ENEAS McCORMICK, a subject of the King of Great Britain, and residing at the city of Calgary, in the Province of Alberta, in the Dominion of Canada, have invented a new and useful Improvement in Foot Cleaners, of which the following is the specification.

My invention relates to improvements in 10 "foot cleaners" to be attached to the running boards of an automobile and is made in the form of a mat.

It consists of a number of rows of short strips of sole leather, placed three together, 15 each row overlapping the other and joined together by iron rods passing through the ends of same. The mat is made the width of the running board and any length desired and has an iron strip at both front and 20 back edges to hold it flat and rigid.

There are two forms of clamps to hold mat to running board, one for a metal and the other for a wooden running board. The clamps are made of iron rods which form 25 the connections for the two outer rows of strips on either end of the mat and are bent over underneath the running board in the form of clamps, which are more particularly hereinafter described.

30 The object of the invention is to provide a means for cleaning mud or soil from a person's shoes before stepping into an automobile, and would be of particular benefit on muddy roads where a person has to get out for repairs or otherwise.

I attain these objects by means of the mechanism as illustrated in the accompanying drawings, in which:—

Fig. 1 is a perspective view of the mat in 40 position on the running board made of metal, with clamp for holding the same.

Fig. 2 is a perspective view of the mat in position on a wooden running board with clamp for holding same.

45 Fig. 3 is a perspective view of a portion of a mat showing the series of three leather strips with the iron rods connecting same, and the washers used to fill in at ends of mat.

Figure 4 is a bottom perspective view.

50 Figure 5 is a perspective detail of the mat and clamp reversed of the form illustrated in Figure 2.

Similar letters refer to similar parts throughout the various views.

55 A is the mat which is composed of a number of rows of short strips B of sole leather

which are in groups of three, each row overlapping the other and being held together by iron rods C. Each row of strips have a sufficient number of groups to cover the 60 width of running board D. At each end of the mat the washers a made of sole leather are placed to act as spacers for the outer rows. The iron strips b and c are placed on either side of the mat as facings and to hold 65 the mat rigid. E is a clamp for a metal running board made out of an iron rod with either end of rod forming the connection for the two outer rows of strips B, and being bent back in the form of a double angle underneath the running board a sufficient distance to ensure a good grip, thence bending back 70 in the centre and turned down in the front at d in the form of a U as a grip or pull which fits underneath the rim e of the running board. The clamp E acts as a spring 75 and presses up against the underside of running board holding the mat tightly in place. To remove the mat the grip d is pulled down below rim e and then pulled 80 straight out.

F is a clamp for a wooden running board made out of an iron rod with either end of rod forming the connection for the two outer rows of strips B and being bent back underneath the running board in the form of an angle and acting as a spring pressing up against the bottom of the board, holding the mat securely in place.

Both the clamps E and F hold by the 90 spring of the U or V portion, as the case may be for the step of the car is between the mat and the inwardly projecting clamping member.

In the clamp E the wire extends inwardly 95 to the extent of the mat and then outwardly to form a U shaped loop.

The application of this foot cleaner is very simple indeed, as the inner portion in both forms is bent downwardly and the mat 100 pushed inwardly until the foot board of the car at its outer edge reaches the outer bend G of the clamp. In this position the U-shaped part is under the foot board in the form illustrated in Figure 1 or the V-shaped 105 part in the form illustrated in Figure 2. In the latter form a screw at the apex of the V is used to prevent the mat sliding outwardly, but this is not required in the first form as the U-clamp fits under the flange of 110 the foot board or plate and locks the mat to its position.

What I claim as my invention is:

A foot cleaner for vehicle steps comprising a mat formed of short links joined together by pintles and a retaining wire the 5 free ends of which form the pintles for certain of the link sections and the intermediate portion being bent downwardly and inwardly between the latter pintles under

the mat to serve as a clamp in holding the mat to the step.

Signed at the city of Calgary, this 26th day of April, 1922.

ÉNEAS McCORMICK. [L.S.]

In the presence of—

J. E. BARTLEY,
FRANCES NOBLE.
